UNITED STATES PATENT OFFICE.

CHARLES C. WORTHINGTON, OF IRVINGTON, NEW YORK.

DESIGN FOR A VALVE-POT.

SPECIFICATION forming part of Design No. 25,622, dated June 9, 1896.

Application filed September 26, 1894. Serial No. 524,202. Term of patent 14 years.

To all whom it may concern:

Be it known that I, CHARLES C. WORTHINGTON, of Irvington, county of Westchester, State of New York, have invented a certain 5 new and original Design for Valve-Pots, fully described and represented in the following specification and the accompanying drawings, forming a part of the same.

This invention relates to a design for a 10 valve-pot for pumps, the invention consisting of a valve-pot having a peculiar shape or configuration, as shown in the accompanying drawings, in which the design is illustrated.

Figure 1 is a side view, and Fig. 2 an edge 15 view, of a valve-pot embodying the design.

The essential feature of the design is the peculiar arrangement of its branches *a b c*,

which connect the valve-pot to the suction, pulsation, and force chambers of a pump, these branches being so disposed relatively to 20 each other that viewing the valve-pot edge-wise, as in Fig. 2, they all lie in the same plane.

What I claim is—

The design for a valve-pot, substantially 25 as shown and described.

In testimony whereof I have hereunto set my hand in the presence of two subscribing witnesses.

CHARLES C. WORTHINGTON.

Witnesses:

LOUIS R. ALBERGER,
B. W. PIERSON.
